(57) **CLAIM**

The ornamental design for an electronic mouse, as shown and described.

DESCRIPTION

FIG. 1 is a front perspective view of an electronic mouse showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a perspective view of an electronic mouse showing an alternative embodiment of our new design;

FIG. 8 is a front view thereof;

FIG. 9 is a rear view thereof;

FIG. 10 is a left side view thereof;

FIG. 11 is a right side view thereof; and,

FIG. 12 is a top view thereof.

The broken line showing of various regions in FIGS. 1-12, including the unshaded areas therein, is for illustrative purposes and forms no part of the claimed design. The unshown bottom of the electronic mouse in FIGS. 1-12 forms no part of the claimed design.
